SPRINKLER NOZZLE UNIT

Robert Nicholas Martin, Long Beach, Calif.

Application November 14, 1955, Serial No. 38,873

Term of patent 3½ years

(Cl. D91—1)

Figure 1 is a side elevational view of a sprinkler nozzle unit showing my new design;

Figure 2 is a front elevational view thereof; and

Figure 3 is a top plan view thereof.

The essential features of my design reside in those portions shown in full lines.

I claim:

The ornamental design for a sprinkler nozzle unit substantially as shown and described.
